UNITED STATES PATENT OFFICE.

CHARLES A. PRESTON, OF CAMBRIDGEPORT, ASSIGNOR TO GEORGE FROST,
GEORGE H. PHELPS, AND GEORGE A. FROST, ALL OF NEWTON, MASSA-
CHUSETTS.

GARMENT-SUPPORTER.

SPECIFICATION forming part of Letters Patent No. 378,148, dated February 21, 1888.

Application filed December 2, 1887. Serial No. 256,778. (No model.)

To all whom it may concern:

Be it known that I, CHARLES A. PRESTON, of Cambridgeport, county of Middlesex, and State of Massachusetts, have invented an Improvement in Garment-Supporters, of which the following description, in connection with the accompanying drawings, is a specification, like letters on the drawings representing like parts.

10 This invention is an improvement upon the garment-supporter shown in United States Patent No. 368,550, granted to me August 16, 1887, and has for its object to provide a locking device which will better hold the button in the 15 button-receiving loop, so that the supporter cannot move freely upon the button.

In accordance with this invention, the locking device is composed of two parts or loops hinged one to the other. One of the said parts 20 or loops of the locking device and the button-receiving loop are hinged or swiveled one to the other, the other part or loop of the locking device being hinged to the aforesaid part or loop, and so as to surround or inclose the 25 button-receiving loop to be moved upon it. The button-receiving loop is substantially as in the patent referred to, it preferably having a broad or expanded portion to receive the button and a narrow portion at its outer end 30 to receive the shank or attaching device or material of the button; and in this my present invention the locking device forces the shank of the button into said narrow portion, or into the outer end of the button-receiving loop, holding it there firmly.

Figure 1 shows in front elevation a garment-supporter embodying this invention. Fig. 2 shows in front elevation a modified form of garment-supporter embodying this invention, and 40 Fig. 3 shows in front elevation another modified form of garment-supporter embodying this invention.

Referring to Figs. 1 and 3, the button-receiving loop is made of wire and has a broad 45 or expanded portion, as *a*, which is narrowed or tapered toward its outer end, as at *a'*. The ends of the wire or material of which the button-receiving loop is composed are turned over to form eyes *a''*, which encircle the material of

that part of the locking device which constitutes the strap-receiving portion *b*. The wire forming the eyes *a''* is so bent as to set the eyes at an angle, in order that they may bind against the wire or other material constituting the strap-receiving portion, and thereby enable the locking device to have a spring-like action, as in the patent referred to. The locking device is herein shown as composed of two parts or loops, as *b* and *b'*, the part or loop *b* having attached to it the strap *c* and the part 55 or loop *b'* engaging the shank or attaching means for the button, which attaching means may be thread or other material. The part or loop *b'* surrounds or incloses the outer end of the button-receiving loop and is hinged or 60 swiveled to the strap-receiving portion at *b''*. The hinge *b''* permits the loop *b'* to be moved toward the strap *c* to expose the broad portion 65 of the button-receiving loop *a*, and thereafter, the button having been passed through said 70 loop *a*, the said loop *b'* will be moved toward the outer end, *a'*, of the button-receiving loop, and thereby force the shank portion of the button into said narrowed or tapered part of the 75 loop and there hold it firmly. Instead of the 80 spring given to the locking device by engaging at one end the outer end of the button-receiving loop and at the other end the inwardly-turned eyes of the button-receiving loop, any suitable spring may be employed.

In Fig. 2 I have shown the strap-receiving portion as a component part of the loop-receiving portion *a*, and the locking device consists of the shank-engaging loop *b'* and a loop, *b*, hinged one to the other, said loop *b* being 85 hinged to the strap-receiving portion of the button-receiving loop. By this modification it will be seen that the same result is obtained as in the form shown in Figs. 1 and 3.

I claim—

1. The herein-described garment-supporter, consisting of the jointed locking device, substantially as herein specified, combined with the button-receiving loop *a*, said locking device and loop being hinged or swiveled one to 95 the other, as and for the purposes set forth.

2. In a garment-supporter, the locking device consisting of two parts or loops, *b* *b'*, hinged

one to the other, combined with the button-receiving loop with which the locking device is connected, substantially as described.

3. The herein-described garment-supporter, consisting of the jointed spring-acting locking device, substantially as herein specified, combined with the button-receiving loop, substantially as and for the purposes specified.

In testimony whereof I have signed my name to this specification in the presence of two subscribing witnesses.

CHARLES A. PRESTON.
